UNITED STATES PATENT OFFICE

2,061,087

STEAM BOILER

John J. Power, Detroit, Mich.

Application August 25, 1934; Serial No. 741,421

3 Claims. (Cl. 122—166)

My invention relates to a new and useful improvement in a steam boiler and has as its object the provision of a boiler which will be light, durable, compact, economical of manufacture and highly efficient in use.

Another object of the invention is the provision of a boiler having a centrally disposed shallow water container so that a very shallow depth of water is subjected to the gases rising to the top of the combustion chamber.

Another object of the invention is the provision of a boiler so constructed and arranged that with a minimum amount of heat expenditure, a maximum amount of steam may be generated.

Other objects will appear hereinafter.

The invention consists in the combination and arrangement of parts hereinafter described and claimed.

The invention will be best understood by a reference to the accompanying drawing which forms a part of this specification and in which

Fig. 1 is a central, vertical, sectional view of the invention.

Fig. 2 is a sectional view taken on line 2—2 of Fig. 1.

Fig. 3 is a fragmentary sectional view taken on line 3—3 of Fig. 2.

Fig. 4 is a sectional view taken on line 4—4 of Fig. 3.

The invention comprises an outer casing or shell 9 which is covered with a layer 10 of heat insulating material. An inner shell 14 is positioned within the outer shell 9 and formed with a flange 14' which is welded or otherwise suitably secured to the surface of the top of the outer shell 9.

Positioned within the intermediate shell 14 is an inner shell 15 having a flange 22 at its lower end which is welded to the inwardly turned flange 21 of the shell 14. The inwardly turned flange 22 on the lower end of the shell 15 rests upon the supporting structure 23 which surrounds the fire pot 24.

A pipe 26 is projected through the casing 9 and the shell 14 to establish communication of the interior of the shell 15, which forms the combustion chamber 25, with the atmosphere. The pipe 26 has a door 27 on its outer end and this pipe 26 is also provided with a plurality of draft openings 28 which are in spaced relation and which may be brought into registration with the openings 30 formed in the band 29 by rotating the band 29 on the pipe 26.

The interior 16 of the shell 14 provides the water container and the space between the shell 14 and the shell 15 serves as a water leg. The upper edge of the shell 15 is turned inwardly

to provide the inwardly projecting, downwardly inclined flange 17 on which is positioned the shallow concave container 18 having the vertically directed lip 19 at its edge. This shallow container 18 is in communication with the water leg 16 adjacent its bottom by means of the tubes 20. The combustion chamber 25 or the interior of the shell 15 is connected by means of the tubular stay-bolts 31 in communication with the flue chamber 32 with which communicates the outlet flue 11. These tubular stay-bolts 31 are spaced circumferentially around the shells 14 and 15 and in addition to binding these parts together serve also as an outlet for the gases which are generated in the combustion chamber 15 and which travel in the direction of the arrows shown in Fig. 1. In order that the gases may travel downwardly to adjacent the bottom of the chamber 32 I have provided spaced partition walls 33. Communicating with the interior of the shell 14 through the top of the shell 9 is a steam outlet pipe 12 which is encased in a layer 13 of suitable insulating material. The fire pot may, if desired, be provided with a grate for fuel on which coal or the like may be used. But I intend that the boiler shall be used primarily with an oil burner. The hot gases arising from the oil burner strike the bottom of the shallow container 18 and on account of the small amount of water in this container steam is very quickly generated. The tubes 20 serve to maintain the water level in the container 18 the same as the water level in the interior of the shell 14. As the gases travel upwardly toward the passages or hollow stay-bolts 31 they will of course heat, to a certain extent, the inner wall 15 of the water leg and the tubes 20, but they will impinge primarily against the container 18 and effect a maximum heating. As these hot gases travel downwardly in the chamber 32 they will still continue to heat the water leg. Thus the gases are brought over a large area of heating surface with the result that the stack temperature is reduced to a minimum and consequently the efficiency of the boiler is raised to a maximum.

With a boiler constructed in this manner it becomes possible to generate steam pressure in a very short time with a minimum fuel consumption. The simplicity and economy of structure is believed obvious from the description given.

While I have illustrated and described the preferred form of construction I do not wish to limit myself to the precise details of structure shown, but desire to avail myself of such varia-

tions and modifications as come within the scope of the appended claims.

Having thus described my invention, what I claim as new and desire to secure by Letters Patent is:

- 5 1. In a boiler, an enclosing shell; an intermediate shell within said enclosing shell in spaced relation thereto, said intermediate shell being connected at its upper and lower ends to said enclosing shell; an inner shell embraced by and spaced from said intermediate shell, the lower edge of said intermediate shell being turned inwardly and connected to said inner shell to provide a water-leg positioned within and spaced 10 from said enclosing shell; an inwardly directed, downwardly inclined, flange on the upper end of said inner shell; an open shallow pan-like structure upon said inwardly directed inclined flange and forming a closure for the top of said inner shell to provide a combustion chamber, the bottom of said pan-like structure being concave, with its convex side directed downwardly; a plurality of tubes communicating with said pan through the bottom thereof and communicating 15 with the interior of the water-leg, the bottom of said pan being positioned normally below the water level of the boiler.
- 20 2. In a boiler, an inverted cup-shaped enclosing shell; an inwardly directed flange on the lower end of said shell; an intermediate shell positioned within and spaced from said enclosing shell and engaging at its upper end with the interior of the top of said enclosing shell and at its lower end with the upper surface of said flange; an inner cylindrical shell positioned within and spaced from said intermediate shell and engaging at its lower end an inwardly directed flange on said intermediate shell to provide therewith a water-leg; an inwardly directed inclined flange

on the upper end of said inner shell; an open shallow pan-like structure having a concave bottom resting upon said inclined flange and serving as a closure for said inner shell to provide a combustion chamber, the convex face of said bottom being directed downwardly; a plurality of tubes for communicating said pan through its bottom with the interior of said water-leg, said pan being positioned downwardly from, and in spaced relation to, the top of said enclosing shell and normally below the water level of the boiler; a plurality of tubes projected through said inner shell and said intermediate shell for establishing communication between the combustion chamber and the space between said intermediate shell 15 and said outer shell, adjacent the top thereof; and an outlet flue communicating with said space, adjacent the bottom thereof.

3. In a boiler, an enclosing shell; an intermediate shell within and spaced at its periphery 20 from said enclosing shell and connected thereto at opposite ends to provide a compartment surrounding said intermediate shell; an inner shell positioned within and spaced at its periphery from said intermediate shell and connected 25 therewith at its lower end to provide a water leg; an open shallow-pan-like structure supported on the upper end of said inner shell and forming a closure for the top of said inner shell to provide a combustion chamber, the bottom of said pan-like structure being concave, with its convex side directed downwardly; and a plurality of tubes communicating with said pan through the bottom thereof and communicating with the interior 30 of the water leg, the bottom of said pan being positioned normally below the water level of the boiler.

JOHN J. POWER.
